UNITED STATES PATENT OFFICE.

JOHN J. MORRISSEY, OF WHITE BEAR LAKE, MINNESOTA.

AUTOMATIC CHECK FOR PHONOGRAFS.

973,205.

Specification of Letters Patent. Patented Oct. 18, 1910.

Application filed July 26, 1909. Serial No. 509,475.

To all whom it may concern:

Be it known that I, JOHN J. MORRISSEY, a citizen of the United States, residing at White Bear Lake, in the county of Ramsey and State of Minnesota, have invented certain new and useful Improvements in Automatic Checks for Phonographs, of which the following is a specification.

This invention relates to improvements in 10 automatic mechanism for stopping the motor of a phonograph when the reproducer has reached the end of the record cylinder.

An object of my invention is to provide 15 an extremely simple and inexpensive device of this character which may be readily attached to phonographs at present constructed and which may be adjusted to conform to the various lengths of the records which are upon the cylinder.

20 Another object is to provide a device which will be automatically set in the proper position for stopping the motor of the machine, when the starting lever has been moved to its proper operative position.

25 A further and more particular object is to provide a controlling lever and support therefor of novel and simple construction.

In the drawings: Figure 1 is a perspective view of the large size type of phonograph, showing the stop mechanism applied thereto, Fig. 2 is a similar view of a smaller size type of machine, with a slight modification of my device, Fig. 3 is a detail view of the controlling lever, comprising my invention.

Referring to Fig. 1 of the drawings, 1 indicates the casing for the motor mechanism, and 2 the frame which supports the phonograph mechanism. This mechanism comprises the main longitudinal shaft 3, the cylinder 4, the feed block 5, the reproducer arm 6, and the reproducer 7. These various elements comprise the principal features of the ordinary phonograph as at present constructed and are suitably connected and operated by the motor mechanism contained within the casing. In this type of machine the stopping lever 8' protrudes from the casing through a slot 9 formed in the base plate 50 of the supporting frame 2, and extends for some distance above the top thereof. To the upper end of this lever one end of the longitudinally extending controlling lever 10 is secured, this lever being supported upon the base plate of the frame 2 by means of links 11 which are pivotally supported upon said

plate and connected to the controlling lever, so that longitudinal movement of the controlling lever will oscillate the starting lever, and the controlling lever will rock upon the links. The other end of the controlling lever 10 is extended rearwardly and upwardly as shown at 12 and its position with relation to the reproducer of the phonograph mechanism, is such that the same will 60 contact with the portion 12 of the controlling lever to stop the operating mechanism, as will be later described. The links 11 are carried by suitable bracket plates 11' having two perforations therein receiving suitable 65 fastening members engaged with a part of the phonograph frame, the plates being provided at one side with an upwardly extended perforated ear 11^a in which there is engaged a suitable pintle, upon which the link is pivotally carried. The brackets 11', the links and the two members of the controlling lever 10 are all formed of sheet metal, which reduces the cost of the device to a minimum 70 and simplifies its construction to a marked 75 degree.

To provide for the stopping of the mechanism at various periods of the longitudinal movement of the reproducer, the arm 12 of the controlling lever is provided with a 80 horizontal extension, which is adjustably secured to the controlling lever 10 and is adjustable with relation to the end of the cylinder. A recess 13 is formed in one side of the controlling lever 10, said recess opening 85 at the end of the lever opposite to the point of connection with the starting lever 8' and this extension 12 has its lower horizontal portion suitably reduced in width and thickness and is disposed slidably within the recess 13, the shoulder formed by the reducing of this horizontal portion being adapted to abut the end of the controlling lever, when at the limit of its inward movement. A longitudinal slot 14 extends the greater 90 portion of the length of the horizontal portion of the member 12, the shank of the set screw 15 being extended through the same, and screw threadedly engaged in the extremity of the controlling lever, by which means it will be seen, that the member 12 95 may be extended outwardly longitudinally of the phonograph cylinder, so that the rearwardly and upwardly extended portion thereof may be disposed to engage the reproducer at the point at which the record of the cylinder terminates. The set screw 15 100 105 110

will secure the member 12 in its adjusted position, and retain the same in such position against any liability of accidental movement so that the lower end of the reproducer 5 will not contact with the extension 12 of the controlling lever until it has reached the end of the cylinder. When this occurs the reproducer will move the controlling lever 10 longitudinally and throw the starting 15 lever 9 to the right, so that the motor mechanism will be instantly stopped. The links 11, which are pivotally connected with the base of the frame 2 will thus be disposed at an inclination to the controlling lever and 20 when the starting lever is again actuated to start the operating mechanism, the controlling lever will be drawn to the left, whereupon the links 11 will again assume their vertical positions and the rearwardly and 25 upwardly extending end portion of the controlling lever will be returned to its normal operative position.

In Fig. 2 I have shown my improved stopping mechanism applied to the smaller type of phonograph now in common use. 25 In this construction of the machine, the main shaft 3', above which the feed block 5 is disposed, is located behind and in parallel relation to the cylinder 4. The reproducer 30 arm is directly connected with the shaft 3', and extends over the front of the cylinder and has secured therein the reproducer 7', thus greatly contracting the length of the machine. The stopping device does not essentially differ from the construction which 35 is employed in the machine shown in Fig. 1. In this form, however, but one link 11' is necessary to support the longitudinal controlling lever 10'. This link is pivoted to the 40 lever and to the base of the supporting frame, and operates in a similar manner to the links 11 as previously described. One end of the controlling lever 10' is secured to the upper 45 end of the starting lever 8', and is adapted to actuate the same to start and stop the operating mechanism when moved to either end of the slot 9'. The other end of the controlling lever is extended rearwardly and 50 upwardly and is adapted to be engaged by the lower end of the reproducer to move the starting lever to the right, when the reproducer has reached the end of the record upon the cylinder. The controlling lever 10' will 55 also be returned automatically to its normal operative position by the movement of the starting lever to the left when it is desired to start the operating mechanism.

From the foregoing it will be seen that I have provided an extremely simple and inexpensively constructed device which may 60 be readily secured upon phonographs of the various types as at present constructed, and requires no especial provision by means of which the same is to be attached to the supporting frame. 65

My improved stop mechanism is particularly adapted for use upon commercial phonographs, where it is essential that the operator should be relieved from the many attentions which it is necessary that he 70 should give to the machine during the transcription of the record. By the use of my improved stop mechanism the operator may give his entire attention to the elucidation of the matter recorded upon the cylinder, 75 whereby much better results may be secured than have heretofore been possible.

What is claimed is:

An automatic stop for phonographs or the like, comprising a combination with a frame, a longitudinally movable reproducer and an oscillating starting lever projecting upwardly through the frame, of a controlling lever secured at one end to the upper end of the starting lever, said controlling 80 lever having a longitudinal recess formed in one side thereof and opening on the opposite end to that secured to the starting lever, a bracket plate secured on the frame below said controlling lever, said plate having an 85 upwardly extending perforated ear, a pintle therethrough, a link pivotally mounted upon said pintle and pivotally connected to said controlling lever intermediate of its length, a rearwardly and upwardly extended arm 90 having a horizontal extension, said horizontal extension being reduced in width and thickness for a greater portion of its length, said reduced portion being provided with a longitudinal slot throughout its length, said 95 reduced portion being slidably mounted in the recess, a set screw extending through said slot and engaged in the extremity of said controlling lever, said arm being adjustably disposed in the path of the reproducer and adapted to actuate said starting lever upon engagement therewith. 100

In testimony whereof I affix my signature, in presence of two witnesses.

JOHN J. MORRISSEY.
